UNITED STATES PATENT OFFICE.

JAMES ALEXANDER MEBANE, OF SOUTH BOSTON, VIRGINIA.

ELECTRIC-LAMP SOCKET.

No. 829,027.

Specification of Letters Patent.

Patented Aug. 21, 1906.

Application filed July 10, 1905. Serial No. 269,101.

To all whom it may concern:

Be it known that I, JAMES ALEXANDER MEBANE, a citizen of the United States, residing at South Boston, in the county of 5 Halifax and State of Virginia, have invented certain new and useful Improvements in Electric-Lamp Sockets; and I do declare the following to be a full, clear, and exact description of the invention, such as will enable 10 others skilled in the art to which it appertains to make and use the same.

My invention relates to improvements in incandescent electric-lamp sockets; and it consists in the novel construction, combination, and arrangement of devices hereinafter 15 described and claimed.

One object of the invention is to provide a simple and efficient connection between the outer shell and cap of devices of this character 20 which will permit them to be quickly and easily connected and disconnected and which will hold them securely together.

Another object of the invention is to improve and simplify the construction of the 25 base-plug within the socket and the electric contact connections thereon, so that the cost of manufacture will be materially reduced.

The above and other objects which will appear as the nature of my invention is better 30 understood, are accomplished by means of the construction illustrated in the accompanying drawings, in which—

Figure 1 is a side elevation of my improved lamp-socket. Fig. 2 is a transverse sectional view, taken on the line 2 2 in Fig. 1. Fig. 3 is a longitudinal sectional view through the socket. Fig. 4 is a perspective view of the base-plug removed from the casing of the socket. Fig. 5 is a horizontal sectional view 40 through the base-plug, and Fig. 6 is a perspective view of the inner side of one of the members of the base-plug. Fig. 7 is a detail sectional view showing a portion of the cap and of the shell detached and in a plane intersecting one of the keepers 4 of the shell and one of the stamped-out clearance portions 6 of the cap.

Referring to the drawings by numeral, 1 denotes my improved lamp-socket, the outer 50 casing of which is composed of a substantially cylindrical casing or shell 2 and a substantially conical cap 3, which closes the open upper end of the shell. My improved connection for securing the cap upon the shell, so 55 that it may be readily applied and removed,

consists in forming in the shell adjacent to its upper end keepers 4, which are preferably in the form of loops stamped out from the shell after making parallel slits therein. One or more of said keepers may be provided; but 60 I preferably have two which are arranged at diametrically opposite points. The lower open end of the cap 3 is provided with spring-tongues 5, which are adapted to enter said keepers or loops 4. These tongues are preferably formed integrally with the cap 3 by cutting portions of the same out, as clearly shown in Fig. 1 of the drawings. The tongues 5 spring inwardly to a slight extent and the portions of the cap adjacent to their 65 free ends are stamped outwardly, as shown at 70 6, so as to receive the keepers or loops 4 when the cap is placed on the shell. The cap is then partly turned upon the shell to cause the tongues 5 to enter said loops. This 75 tongue-and-loop connection prevents longitudinal movement of the cap upon the shell, and to prevent rotary movement between said parts, so that the tongues will be held in the loops, I form in the shell 2 one or more 80 detents 7, which are adapted to engage seats 8, formed in the cap 3. Any number of these detents may be provided, but, as shown, I have arranged two midway between the keepers 4 and have formed them by stamping a portion of the shell outwardly to form a slight projection. The seats 8 may be similarly formed; but, as illustrated, they are in the form of openings or apertures cut in the cap and adapted to receive the projections or 85 90 detents 7, as clearly shown in Figs. 1 and 2 of the drawings. It will be seen that this construction permits the cap and shell to be quickly and easily secured together in a manner that will effectively prevent them from 95 being casually disconnected. The lower portion of the shell 2 is preferably of polygonal form in cross-section, so that spaces or channels 10 will be formed between it and the base-plug 11, which is inserted in the shell 100 through its open top. Within the shell 2 I preferably provide a lining 12 of suitable insulating material.

The base-plug 11, upon which the various electrical contact-plates and connections are 105 mounted, is formed of two half-sections 13 14, which are secured together by a screw 15 and by the usual screw-shell 16, into which the threaded portion of an incandescent electric lamp is adapted to be screwed. This 110

shell 16 is screwed upon the lower end of the two parts of the base-plug, which is reduced and screw-threaded, as shown at 17. The screw 15 passes through alining openings in 5 the members or sections 13 14 and into a threaded opening in a key-supporting plate 18. The latter is of substantially U form and is secured by said screw 15 in a recess 19, formed in the outer face of the member 13. 10 This plate 18 has a set-screw 20, to which one terminal of the electrical conductor 21 may be attached, and journaled in its two arms is the stem 22 of the operating-key. This stem extends through a slot formed in 15 the shell 2 and has upon its outer end an insulated finger-piece 23. The stem is retained in its bearings by a cross-pin 24 and has its inner end enlarged, as shown at 25, to actuate a rotary contact-block 26, which is 20 pivotally mounted in the plate 18 concentric with the key-stem and has formed in its outer face a recess 27 of slightly less width than the enlargement or head 25 upon the stem, so that said enlargement actuates the 25 block when the stem is turned. The contact-block 26 is moved by the stem into and out of electrical contact with a projecting portion 28, formed upon the screw-shell 16, and it is adapted to be held in either its open 30 or closed position by a spring 29, secured upon the plate 18. The other terminal of the electrical conductor 21 is attached to a set-screw 30, provided upon a contact-plate 31, which is disposed in a recess 32, formed 35 in the member 14 of the base-plug. The recess 32 extends from the outer face of the member 14 through to the inner face and bottom of the same, and the contact-plate 31 has its lower end bent to form a contact-but- 40 ton 33, which is seated in a recess 34, formed partly in the bottom of the member 13 and partly in the member 14. The electric circuit through the socket will be readily seen upon reference to the drawings. The contact-plate 31 is retained in the recess 32 of 45 the member 14 by a screw 35, which passes through an opening formed in the inner face of the member 14, as shown.

The construction, operation, and advan- 50 tages of the invention will be readily understood from the foregoing description, taken in connection with the accompanying drawings. By making the base-plug 11 in two sections 13 14, as shown, and mounting the 55 contact-plates 18 and 31, as described, it will be seen that the parts may be manufactured at a much reduced cost and may be quickly assembled.

While I have shown and described the pre- 60 ferred embodiment of the invention, it will be understood that I do not wish to be limited to the precise construction herein set forth, since various changes in the form, proportion, and the minor details of construc- 65 tion may be resorted to without departing

from the principle or sacrificing any of the advantages of this invention.

Having thus described my invention, what I claim as new, and desire to secure by Letters Patent, is—

1. An electric-lamp socket-cap having a laterally-extending tongue and an outstanding clearance portion 6 near the free end of the tongue, in combination with a shell having a keeper to enter the clearance portion 6 75 when the cap is placed on the shell and to receive the tongue when the cap is partly turned on the shell, substantially as described.

2. An electric-lamp socket-cap having a laterally-extending tongue and an outstanding clearance portion 6 near the free end of the tongue, in combination with a shell having a keeper to enter the clearance portion 6 when the cap is placed on the shell and to receive 85 the tongue when the cap is partly turned on the tongue, said cap and shell being further provided with coacting devices to prevent casual angular motion of one on the other, after the tongue and cap have become 90 engaged.

3. In a fastening, the combination of two members, one having a keeper-loop and the other a tongue to enter said loop and prevent longitudinal movement of said members 95 upon each other, and one having a detent projection and the other a seat to receive said projection to prevent rotary movement of said members upon each other.

4. In a fastening, the combination of two members, one being formed with an integral, longitudinally-extending, loop and the other with a tongue to enter said loop to prevent longitudinal movement of the members upon each other, and one of said members having a 105 detent projection stamped upwardly therefrom and adapted to enter a seat or opening formed in the other of said members to prevent rotary movement of said members with respect to each other.

5. An electric-lamp socket having a base- 110 plug composed of two semicylindrical sec- tions, each having reduced screw-threaded lower portions and one of said sections hav- 115 ing a recess in its outer side, a screw-shell on the threaded portion of said sections securing them together, and having a contact portion in said recess, and a key mounted in said re- 120 cess and having a contact-block to engage and disengage said contact portion of the screw-shell, substantially as described.

6. An electric-lamp socket comprising a base-plug divided longitudinally into two substantially semicylindrical members hav- 125 ing their lower reduced ends screw-threaded, one of said members being formed with a re- 130 cess in its outer face and the other with a re- cess in its outer and inner faces, a screw-shell upon the threaded ends of said members, a terminal contact-plate secured in the recess

of one of said members and having a contact-button disposed in the threaded end of said members, a substantially U-shaped plate in the recess of the other of said members, a screw extending through said members and into said U-shaped plate, a rotary stem mounted in said U-shaped plate, a contact-block adapted to be actuated by said stem and to be moved into and out of contact with said screw-shell, and a spring for hold-

ing said block in an adjusted position, substantially as described.

In testimony whereof I have hereunto set my hand in presence of two subscribing witnesses.

JAMES ALEXANDER MEBANE.
